UNITED STATES PATENT OFFICE.

GEORGE W. P. OVERMAN, OF NORFOLK, VIRGINIA.

LIFEBOAT SECURING AND RELEASING MECHANISM.

Application filed November 11, 1926. Serial No. 147,773.

This invention relates to a life boat securing and releasing mechanism embodying chocks from which the life boat may be swung laterally or in an outward direction, 5 means holding the life boat against lateral displacement from the chocks, and means holding the life boat against vertical displacement from the chocks.

The invention has for one of its objects 10 to provide a mechanism of the character set forth wherein the means for holding the life boat against lateral displacement from the chocks shall embody pivoted jaws having vertical and horizontal keel contacting members of which the latter constitute rests 15 for the keel and are movable with and with respect to the jaws during the movement of the jaws into life boat retaining or releasing position so as to render it impossible for the 20 keel to interfere with the free movement of the jaws into either of and especially the last named of said positions.

A further object of the invention is to 25 provide a mechanism of the character set forth which shall include means for moving the jaws into life boat retaining or releasing position and which shall be directly connected to the movable members of the jaws so as to actuate them in a manner to render 30 it impossible for the keel to interfere with the free movement of the jaws into either of its positions.

A further object of the invention is to 35 provide a mechanism of the character stated wherein the means for holding the life boat against vertical displacement from the chocks shall embody hooks connected to the life boat, chains connected to the deck of the vessel, catches releasably connecting the 40 chains to the hooks and adapted to be restrained in order to maintain the connection, and catch restraining means.

A still further object of the invention is 45 to provide a mechanism of the character set forth which shall embody means associated with the jaw actuating means and adapted to secure the catch restraining means to a fixed part of the vessel while the jaws are in life boat retaining position and adapted 50 to release the restraining means during the movement of the jaws into life boat releasing position.

The invention is hereinafter more fully described and claimed, and illustrated in the accompanying drawings, wherein:

Figure 1 is an elevational view illustrating the application of the life boat securing and releasing mechanism,

Figure 2 is a sectional view taken on the vertical plane indicated by the line 2—2 of 60 Figure 1,

Figure 3 is a detail top plan view illustrating the locking means for the catch restraining means,

Figure 4 is a sectional view taken on the 65 vertical plane indicated by the line 4—4 of Figure 3,

Figure 5 is a detail elevational view of one of the jaws in boat retaining position,

Figure 6 is a view in side elevation of the 70 part shown in Figure 5.

Figure 7 is a view similar to Figure 6 with the jaw in life boat releasing position.

Figure 8 is a sectional view taken on the 75 horizontal plane indicated by the line 8—8 of Figure 6,

Figure 9 is a detail elevational view of 80 one of the catches by which the restraining means are secured to the hooks carried by the boat,

Figure 10 is a view in side elevation of 85 the catch illustrating the manner in which it automatically disengages from the hooks when the catch restraining means is released,

Figure 11 is a view similar to Figure 10 illustrating the catch in locked engagement with the hooks, and

Figure 12 is a detail sectional view taken 90 on the vertical plane indicated by the line 12—12 of Figure 9.

Referring in detail to the drawings, in the several views of which like reference characters denote like parts, 1 designates the deck of a vessel, 2 a life boat which is 95 supported from davits 2 by tackles 3, and 4 chocks upon which the life boat rests. The upper edges 5 of the chocks 4 conform to the curvature of the inboard under side of the life boat. The chocks 4 are provided at their 100 outboard ends with vertical edges 6 and below the same with outwardly projecting extensions 7. The upper edges 8 of the extensions 7 incline downwardly and outward-

ly, and secured to said edges thereof are straps 9. Jaws 10, which are normally supported in a vertical position, function to retain the life boat 2 on the chocks 4 against lateral or outboard displacement. The jaws 10 are of U-form in cross or horizontal section, and are provided at their lateral sides with downwardly extending lugs 10^a which are pivoted as at 11 to the straps 9. The jaws 10 are provided at their upper ends with vertical and horizontal members 12 and 13, respectively, which in conjunction with the edges 6 of the chocks 4 provide a channel for the reception of the keel 2^a of the life boat 2. The members 12 are formed integrally with and extend upwardly from the outboard sides of the jaws 10 and contact with the outboard side of the keel 2^a. The members 13 are pivoted to and between the lateral sides of the jaws 10 by bolts 14 and the keel 2^a rests thereon.

A rock shaft 15 is journaled in the chocks 4, and is provided at one end with a handle 16 and between its ends with cranks 17. The axis of rotation of the shaft 15 is located inwardly of and slightly below the axis of rotation of the jaws 10. Links 18 are fixed to the jaw members 13 and pivoted as at 19 to the upper ends of the cranks 17. The connection between the jaws 10 and shaft 15 is such as to adapt the shaft to be used for lowering the jaws into their life boat releasing position shown in Figures 7 and 8, and for raising them into their life boat retaining position, shown in Figures 2, 5 and 6. During the movement of the jaws 10 into their life boat releasing and retaining positions, the members 13 move with the jaws with respect thereto, with the result that during the first phase of their downward movement and during the final phase of their upward movement they travel in a plane substantially at right angles to the bottom of the keel 2^a. It will thus be seen that the jaws 10 can be freely moved into either of their positions and that they cannot be locked by the keel 2^a against movement into life boat releasing position. The shaft 15 is also adapted to be used for the purpose of locking the jaws 10 in their life boat retaining position, and to attain this end there is employed a member 20 which is carried by the life boat 2 and removably engaged with the handle 16.

The life boat 2 is held against vertical displacement from the chocks 4 by chains 21 which are secured at their lower ends to rings 21^a fastened in any suitable manner to the deck 1. The upper ends of the chains 21 are detachably connected to hooks 22 which are engaged with the gunwales of the life boat 2 and have vertically depending shanks 22^a. The hook shanks 22^a are provided with eyes 23 and below the same with slots 24. The chains 21 are secured to the

hooks 22 by catches 25 of which each comprises relatively long and short members 26 and 27 respectively, the member 26 being pivoted at one end as at 28 to the member 27 at a point intermediate the ends of the latter. The catch members 26 are provided with hooked portions 29 which engage the hook shanks 22^a by extending through the slots 24 thereof. The catch members 27 are provided with reduced upper ends 30 which extend upwardly through the eyes 23 carried by the hook shanks 22^a. The lower ends of the catch member 27 are provided with hooks 31. Clevises 32 are pivoted as at 33 to the catch members 26, and the upper ends of the chains 21 are adjustably connected to the clevises by bolts 34. The catch members 26 and 27 are prevented from having any relative pivotal movement, and are thus held against casual disengagement from the hooks 22 by means of chains 35 which are engaged at their upper ends with the hooks 31 of the catch members 27. The lower ends of the chains 35 are secured to rings 36 which are normally retained in engagement with the upwardly extending lugs 37 of plates 38, by lock blocks 39 secured to the shaft 15. The plates 38 are secured to the deck 1 below the shaft 15, and each plate is provided adjacent its ends with a pair of the lugs 37. The inner or contiguous edges of the lugs 37 incline upwardly and outwardly so as to permit the rings 36 when released to move freely out of engagement with the lugs. The lock blocks 39 extend downwardly from the shaft 15 and contact with rings 36 in a manner to hold them in engagement with the lugs 37. The lock blocks 39 are in ring retaining position when the jaws 10 are in life boat retaining position, and in ring releasing position when the jaws are in life boat releasing position. The lock blocks 39 are of sectional formation to permit them to be readily applied to the shaft 15 after it has been passed through the chocks 4, and the sections thereof are secured together by bolts 40 and by tongues 41 carried by certain of the sections and fitting in recesses 42 in the others.

From the foregoing, taken in connection with the accompanying drawings, it will be apparent that the life boat may be easily and quickly released from the chocks 4, and that to release the life boat it is only necessary to free and turn the shaft 15. The turning of the shaft 15 will swing the jaws 10 and lock blocks 39 into life boat and ring releasing position. As the chains 35 are not now under restraint, the weight of the chains 21 will cause the catch members 26 and 27 to swing on their pivots 28, with the result that they will be automatically disengaged from the hooks 22 and the life boat freed from all deck securing.

It should be understood that the draw-

ings are merely illustrative and do not pretend to give exact proportions. Furthermore, the said drawings are illustrative of a preferred construction, it being my expectation that various changes and modifications may be made without departing from the spirit and scope of my invention.

What is claimed is:—

1. A life boat securing and releasing mechanism, including chocks from which the boat may be swung in an outboard direction, pivoted elements adapted to contact with the outboard side of the keel of the boat to hold the latter against outboard displacement from the chocks, members movably connected to the elements and constituting rests for the keel, and means for holding the elements in boat retaining position and for moving them into boat releasing position and at the same time moving the members with respect to the elements.

2. A life boat securing and releasing mechanism, including chocks from which the boat may be swung in an outboard direction, pivoted jaws having vertically disposed keel contacting members, horizontally disposed keel contacting members pivoted to the jaws, and locking and actuating means for the jaws connected to the pivoted members.

3. A life boat securing and releasing mechanism, including cocks from which the boat may be swung in an outboard direction, pivoted jaws provided with vertically disposed keel contacting members, horizontally disposed keel contacting members pivoted to the jaws, a shaft provided with cranks, members connected to the pivoted members and cranks, and means for securing the shaft against casual movement.

4. A life boat securing and releasing mechanism, including chocks from which the boat may be swung in an outboard direction, pivoted jaws having vertically disposed keel contacting members, horizontally disposed keel contacting members pivoted to the jaws above the pivots of the latter, a shaft spaced inwardly from and in substantial alignment with the pivots of the jaws, cranks secured to the shaft, arms connected to the pivoted members and cranks, and means for securing the shaft against casual movement.

5. A life boat securing and releasing mechanism including members secured to the boat, members secured to the deck of the vessel, catches releasably connecting the members and adapted to be restrained to maintain the connection, restraining members for the catches, and locking means for the restraining members.

6. A life boat securing and releasing mechanism including members secured to the boat, members secured to the deck of the

vessel, catches releasably connecting the members and adapted to be restrained to maintain the connection, restraining members for the catches provided with rings, members with which the rings are engaged, and means normally holding the rings in engagement with the last named members.

7. A life boat securing and releasing mechanism including members secured to the boat, members secured to the deck of the vessel, catches releasably connecting the members and adapted to be restrained to maintain the connection, restraining members for the catches and provided with rings, plates provided with lugs with which the rings are engaged, a shaft, locking blocks carried by the shaft and contacting with the rings, and means securing the shaft against casual rotation.

8. A life boat securing and releasing mechanism including members secured to the boat, members secured to the deck of the vessel, catches releasably connecting the members and adapted to be restrained to maintain the connection, restraining members for the catches, and locking means for the restraining members, each catch embodying pivotally connected members removably engaged with the boat carrying members, the members secured to the deck being engaged with certain of the members of the catches and the restraining members being engaged with the other members of the catches.

9. A life boat securing and releasing mechanism including hooks connected to the boat and provided with eyes and slots, catches embodying pivotally connected members engaged with the hooks through the medium of the eyes and slots, members secured to certain of the catch members and to the deck of the vessel, and catch restraining means connected to the other members of the catches.

10. A life boat securing and releasing mechanism including hooks connected to the boat, catches releasably connected to the hooks and adapted to be restrained to maintain the connection, members secured to the catches and to the deck of the vessel, and catch restraining means.

11. A life boat securing and releasing mechanism including hooks connected with the boat, pivotally connected members releasably engaged with each hook, an element secured to one of the members and to the deck of the vessel, and a member secured to the other member and to the deck of the vessel and adapted to maintain the members in engagement with the hooks.

12. A life boat securing and releasing mechanism including chocks from which the boat may be swung in an outboard direction, pivoted jaws adapted to contact with the

keel of the boat to hold the boat against outward displacement from the chocks, hooks engaged with the boat, members secured to the deck of the vessel, catches releasably connecting the members to the hooks and adapted to be restrained to maintain the connection, and means adapted to support the jaws

in boat retaining position and to restrain the catches, said means being adapted to be operated to simultaneously move the jaws ¹⁰ into boat releasing position and to release the catches.

In testimony whereof I affix my signature.

GEORGE W. P. OVERMAN.
